DESIGN FOR A SERVIETTE HOLDER

Rosa M. Thamm, Berkeley, Calif.

Application October 27, 1937, Serial No. 72,468

Term of patent 14 years

To all whom it may concern:

Be it known that I, Rosa M. Thamm, a citizen of the United States, residing at Berkeley, in the county of Alameda and State of California, have invented a new, original, and ornamental Design for a Serviette Holder, of which the following is a specification, reference being had to the accompanying drawing, forming a part thereof.

The figure is a perspective view of a serviette holder showing my new design.

I claim:

The ornamental design for a serviette holder substantially as shown.

ROSA M. THAMM.
